Primary Examiner — Darlington Ly*Assistant Examiner* — Giang Hoang Tran(74) *Attorney, Agent, or Firm* — Saidman DesignLaw Group, LLC(57) **CLAIM**

The ornamental design for an electric motor vehicle as shown and described.

DESCRIPTION

FIG. 1 is a top, front and left side perspective view of an electric motor vehicle showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.
